FOREIGN PATENT DOCUMENTS

WO WO 2006/094258 A1 9/2006

Primary Examiner — Mimosa De(74) *Attorney, Agent, or Firm* — McDermott Will & Emery LLP(57) **CLAIM**

We claim the ornamental design for a seating unit, as shown and described.

DESCRIPTION

FIG. 1 is a front perspective view of a seating unit according to the new design;

FIG. 2 is a rear perspective view of a seating unit shown in FIG. 1;

FIG. 3 is a front view of the seating unit shown in FIG. 1; FIG. 4 is a rear view of the seating unit shown in FIG. 1; and, FIG. 5 is a left side view of the seating unit shown in FIG. 1, the opposed right side view being a mirror image thereof. In the drawings, the broken lines form no part of the claimed design.
